(57) **CLAIM**

I claim the ornamental design for a cup holder liner, as shown and described.

DESCRIPTION

FIG. 1 is a perspective view showing my new design for a cup holder liner.

FIG. 2 is a top view thereof.

FIG. 3 is a bottom view thereof.

FIG. 4 is a right side view thereof.

FIG. 5 is a left side view thereof.

FIG. 6 a front view thereof.

FIG. 7 is a rear view thereof; and,

FIG. 8 is a second perspective view thereof, shown in environmental use.

The broken lines represent unclaimed subject matter and form no part of the claimed design.
